UNITED STATES PATENT OFFICE.

BENJAMIN S. MOORE, OF WILKINSBURG, PENNSYLVANIA, ASSIGNOR TO WESTINGHOUSE ELECTRIC & MANUFACTURING COMPANY, A CORPORATION OF PENNSYLVANIA.

BRUSH-HOLDER ROCKER RING.

Application filed January 20, 1921. Serial No. 438,583.

To all whom it may concern:

Be it known that I, BENJAMIN S. MOORE, a citizen of the United States, and a resident of Wilkinsburg, in the county of Allegheny and State of Pennsylvania, have invented a new and useful Improvement in Brush-Holder Rocker Rings, of which the following is a specification.

My invention relates to dynamo-electric machines and it has particular relation to brushholder rocker rings therefor.

One of the objects of my invention is to provide a brushholder rocker ring that may be moved angularly with respect to the axis of the machine for the purpose of obtaining access to the respective brushes mounted thereon and is especially adapted for employment in railway motor construction where accessibility is a vital feature.

Another object of my invention is to provide a device of the character described that may be accurately positioned adjacent to the axis of sparkless commutation after having been temporarily displaced for the purpose of adjustment or repairs to the brushes.

Another object of my invention is to provide means for securely fastening the rocker ring in interlocking engagement with the frame of the dynamo-electric machine.

In the accompanying drawings,

Figure 1 is a fragmentary view, partially in elevation and partially in vertical longitudinal section, of a dynamo-electric machine embodying my invention.

Fig. 2 is a transverse vertical sectional view, taken on line II-II of Fig. 1, illustrating the means for expanding the rocker ring into interlocking engagement with the frame of a dynamo-electric machine.

Referring to the drawings, a dynamo-electric machine is shown as having a frame 1 and a commutator cylinder 2. An annular channel member 3 is suitably secured to the interior surface of the frame 1 and adjacent to the commutator end of the machine. A rocker ring 4 is mounted within the channel 3 and is provided with a plurality of brushholder arms 5 which extend outwardly therefrom and overhang the commutator 2. A plurality of brushholders

6, having brushes 7, are suitably secured to the arms 5 for co-operation with the commutator cylinder 2.

The ring 4 is preferably split, as at 7', the respective ends thereof being beveled, as indicated at 8. A wedge 9 is provided with a bolt 10 which extends vertically through an aperture 11 in the frame 1 of the machine and is adapted to draw the wedge member 9 into engagement with the beveled portion 8 of the rocker ring to expand the same within the channel 3 and into frictional engagement with the inner surface thereof.

When it is desired to rotate the ring into a position where access may be readily had to the brushes, the bolt 10 and the wedge 9 are removed from the machine, permitting the ring 4 to contract sufficiently to allow the same to be rotated within the channel 3.

In accordance with my invention, a rocker ring may be moved to a position where access may be readily obtained to the brushholders and brushes and be returned to a predetermined position with respect to the field without the necessity of delicate adjustment. Furthermore, after the ring has been once locked in position, it will be impossible for it to become displaced circumferentially and thereby disturb commutating conditions.

I claim as my invention:

1. In a commutator-type dynamo-electric machine, the combination with the frame thereof, of means for providing, in effect, an annular channel therein, a split brushholder rocking ring rotatably mounted in said channel, and means engageable with said frame only at a predetermined point for coacting with the split ends of said ring and expanding said ring into interlocking engagement with said channel, whereby the brushholder ring may be readily moved to a temporary position and restored to normal position without loss of adjustment of the commutating brush axis.

2. A dynamo-electric machine provided with an annular channel disposed adjacent to one end thereof, a brushholder rocker ring movably mounted in said channel, said ring being provided with a split portion, a wedge member adapted to coact with said

split portion to expand said ring into interlocking engagement with said channel, and means associated with said wedge member for predetermining its position with respect to said channel.

3. A dynamo-electric machine having a brush-holder rocker ring adapted to be

moved angularly with respect to the axis of said machine, and means for locking said ring only in a predetermined position.

In testimony whereof, I have hereunto subscribed my name this 11th day of January, 1921.

BENJAMIN S. MOORE.
